UNITED STATES PATENT OFFICE.

CARL HANER, JR., OF SUFFERN, NEW YORK, ASSIGNOR TO AMERICAN BRAKE SHOE & FOUNDRY COMPANY, OF MAHWAH, NEW JERSEY, A CORPORATION OF NEW JERSEY.

BRAKE-SHOE.

1,182,368.

Specification of Letters Patent.

Patented May 9, 1916.

Application filed March 23, 1916. Serial No. 86,054.

To all whom it may concern:

Be it known that I, CARL HANER, Jr., a citizen of the United States, and a resident of Suffern, in the county of Rockland and State of New York, have made and invented certain new and useful Improvements in Brake-Shoes, of which the following is a specification.

My invention relates to composition filled brake shoes. In this type of shoe it is essential that a large area of composition filling be provided, and to this end the body portion of the shoe is constructed in the form of a shell. The side walls of this shell, being of limited thickness and formed of cast iron, are oftentimes fractured and broken during the forced insertion of the composition filling, or by the bulging and spreading of such filling upon the application of the brake shoe to a car wheel. The fracture or breakage of these side walls, which may also take place during handling, allows the composition filling to become loosened and dislodged from the shell. The limited thickness of the side walls of the shell is also objectionable, due to its action when contacting with the tread of a car wheel.

It is therefore an object of the present invention to provide a composition filled shoe wherein the cast iron body or shell is reinforced throughout, and the side walls are prevented from becoming fractured and broken, and the composition filling from becoming dislodged.

A further object is to accomplish the aforementioned ends in a manner such that a composite wearing surface is provided for the thin and narrow side walls of the shell, preventing these side walls from scoring or cutting the tread of a car wheel, or becoming prematurely worn away.

With these and other objects in view, my invention resides in the combination and arrangement of parts, and in the details of construction, hereinafter described and claimed, and illustrated in their preferred embodiment in the accompanying drawings, wherein:—

Figure 1 is a view in perspective of the shell or body portion of my improved brake shoe, portions of one of the side walls thereof being broken away; Fig. 2 is a top plan view of the foregoing, with a portion thereof in section, illustrating the arrange-

ment of the reinforcements of ductile metal: 55 Fig. 3 is a view in section taken on the line 3—3 of Fig. 2; Fig. 4 is a view in section similar to the foregoing, of a slightly modified form of shoe, the reinforcements of ductile metal in this type of shoe extending entirely across the back, as well as around the side and end walls of the shell; Fig. 5 is a fragmental view in perspective of this latter type of shoe, a portion of the cast iron and one end of the body of the shoe being 65 broken away.

Referring specifically to the several views, my improved brake shoe is preferably, though not necessarily, formed with a steel back 10, to which is cast a body 11, in 70 the form of an open box or shell. The shell is formed with the single compartment 12, which extends throughout the length and breadth of the shoe, so as to receive the continuous and unitary mass of composition 75 filling therein. In order that the brake shoe will possess the requisite wearing and frictional qualities, it is necessary that a large wearing area of composition filling be provided, so that the side and end walls 14 and 80 15 of the shell must necessarily be made on limited thickness.

Incorporated within the side and end walls of the shell, are the reinforcements 85 16 of expanded ductile metal. These reinforcements may terminate at the rear surface of the shoe, as illustrated in Fig. 3, or may continue across the back of the shoe, as illustrated in Fig. 4, in which latter case the reinforcing steel back 10 of the shoe may be 90 omitted if desired. The reinforcements, being made of ductile metal, and the walls of the shell being formed of cast iron, collectively form composite wearing surfaces, preventing the too rapid wear of the side walls 95 of the shell, or their scoring of the tread of the car wheel. Further, the presence of ductile reinforcements prevents the side walls from being broken, either by rough handling, or the occurrence of excessive transverse stresses, such as during the forced insertion and packing of the composition filling, or the subsequent bulging of the filling during the application of the brake shoe to a car wheel.

What I claim is:—

1. A shell for composition filled brake shoes comprising a cast metal body with

- side and end walls of limited thickness, and reinforcements of openwork ductile metal embodied in the said side walls.
2. A brake shoe shell comprising a cast metal body with spaced side and end walls of limited and substantially uniform thickness throughout, and reinforcements of openwork ductile metal incorporated in said side walls.
- 10 3. A brake shoe comprising a shell formed of cast iron, with side and end walls of limited thickness, a reinforcing strip of openwork ductile metal embodied in the walls of said shell, and a composition filling 15 contained within said shell.
4. A brake shoe comprising a shell formed of cast iron, and including side and end walls of limited, and substantially uniform, thickness throughout, openwork ductile metal reinforcements embodied in said shell 20 walls, and a composition filling contained within said shell.

Signed at Suffern, in the county of Rockland and State of New York this 20th day of March A. D. 1916.

CARL HANER, JR.
